UNITED STATES PATENT OFFICE

ROSCOE H. WILMETH, OF SPRINGFIELD, ILLINOIS, ASSIGNOR TO SANGAMO ELECTRIC COMPANY, OF SPRINGFIELD, ILLINOIS, A CORPORATION OF ILLINOIS

ELECTRIC CLOCK

Application filed May 10, 1930. Serial No. 451,216.

The present invention relates to electric clocks, and particularly to striking clocks adapted to strike at certain time periods, such as on the hour, half hour, etc.

Electric clocks are now generally provided with an electrically operated means for operating the striking mechanism. This provision usually consists of the employment of an electric motor in addition to the conventional winding motor, which is continuously connected across the current supply line. While this arrangement has an advantage in that the operation of the striking mechanism in no way affects the timing characteristics of the clock, there are nevertheless several major objections thereto. It will be apparent that in such a construction, if the current supply fails prior to a striking period, the striking mechanism must necessarily remain silent. Furthermore, two motors must necessarily be employed in such an arrangement, thus materially increasing the manufacturing costs of this type of striking clock.

The present invention contemplates the employment of the winding motor to operate the striking mechanism during a striking period, at the same time permitting the main spring of the clock to act on the striking mechanism to a slight degree. Thus, should the current supply fail during a striking period, provision is made for carrying over of the operation of the striking mechanism by the main spring. These functions are accomplished by the interposition of a differential gear in the series of reduction gears between the main spring and the winding motor. This differential gear is adapted to transmit power from the winding motor to the striking mechanism during a striking period without producing any winding effect on the main spring, which during a striking period is adapted to unwind somewhat in spite of the operation of the winding motor. Thus, during a striking period, all the energy transmitted to the clock mechanism by the winding motor is absorbed by the striking mechanism. This is accomplished by so arranging the reduction gears that the maximum rate at which the motor can wind the

main spring is always somewhat less than the rate of unwinding of the main spring during the striking operation, with the result that with the power either on or off, the main spring is unwinding slightly during a striking period.

With the above in view, the main object of this invention is to provide a striking clock wherein the operating energy for the time keeping mechanism and for the striking mechanism is derived electrically, as from the ordinary house lighting circuit.

Another object is to provide a striking mechanism operable by a winding motor for the main spring or by the main spring.

A further object is the provision of a novel gear connection between the winding motor and the main spring so that the main spring at all times acts to limit the amount of energy delivered by the motor to the striking mechanism.

Another object is the provision of a novel gear connection between the winding motor and the main spring so that all the energy delivered by the winding motor is taken up by the striking mechanism during a striking period.

A further object is to provide such a gear arrangement that the striking mechanism will operate regardless of the condition of the winding motor.

Another object is to provide a gear arrangement whereby the main spring will unwind during a striking period even though the winding motor is operating.

A further object is the provision of a novel gear arrangement whereby the maximum speed at which the motor can wind the main spring is always somewhat less than the rate of unwinding of the main spring during a striking operation.

Another object is to provide a novel striking means whereby clearly distinguishable audible signals are emitted at predetermined time periods such, for example, as hourly and half-hourly periods by the operation of a single operating mechanism. This is accomplished by the provision of two coacting striking hammer arms having a lost motion provision therebetween whereby both arms

may be actuated in unison or one of them without the other. Thus at the hour interval, two gongs are struck while on the half-hour only one is struck. In conjunction with 5 this portion of the mechanism, a control means has been provided for rendering one of the arms ineffective at the half-hour period.

Other and further objects will appear from 10 the following detailed description of an embodiment of my invention illustrated in the accompanying drawings in which:

Figure 1 is a fragmentary elevational view 15 of a clock, portions thereof being broken away to illustrate the striking mechanism control elements;

Figure 2 is an elevational section of the 20 clock frame behind the front frame plate, and showing the reduction gears from the winding motor to the main spring;

Figure 3 is a section similar to Figure 2, taken along a plane closer to the rear frame plate and illustrating the striking mechanism;

25 Figure 4 is a transverse section of the clock mechanism taken along the line 4—4 of Figure 2;

Figure 5 is a transverse section of the 30 striking mechanism taken along the line 5—5 of Figure 3 and showing the differential gear in section;

Figure 6 is a detailed view of the differential gear; and

35 Figure 7 is an enlarged perspective detail of the hammer arm mounts illustrating the lost motion provision therebetween.

The operating parts of the clock may be 40 enclosed in a housing of any preferred design, with striker gongs 11 and 12 disposed either to one side of or below the clock mechanism proper. The clock movement is assembled between the front and rear frame plates 13 and 14, which are held in spaced relation by intermediate spacing posts 15.

45 An electric motor mechanism 16 for winding the clock movement and for operating the striker mechanism is preferably mounted on the rear side of the rear frame plate 14. This motor may be of any type or construction capable of remaining in a stalled position over indefinite time periods, and is directly connected across the line. Preferably, this motor is an alternating current induction motor of the general construction disclosed in the copending application of Frederick C. Holtz, Serial No. 750,201, filed November 15, 1924.

I shall first describe the driving train of 50 the clock to illustrate its correlation with the striking mechanism and the winding operation. In the exemplary construction shown, the armature shaft 21 of the clock motor 16 extends through the rear plate 14 of the frame and carries a pinion 22 which 55 meshes with a spur gear 23 on an arbor 24.

It will be understood that the gear train which I am about to describe is disposed between the spaced frame plates 13 and 14 and that the several arbors to which reference shall be made are journalled at their front and rear ends in these plates, respectively. Mounted on the arbor 24 is a pinion 25 which meshes with a large gear 26 on a second arbor 27. This latter arbor carries a pinion 28 which meshes with a large gear 29 on a third arbor 31 to which a pinion 32 is secured. The latter pinion 32 meshes with a bull gear 33 of a spur-gear differential, generally indicated at 34.

Referring particularly to Figure 5, the 80 differential 34 comprises the bull gear 33 which carries thereon two diametrically disposed differential pinions 36 rotatably mounted on shafts 37 which have their end portions cut away to form flat, diametric surfaces 38. The shafts 37 are seated in recesses 39 with the flat end surfaces in alignment with the rear surface of the bull gear 33, and are retained in fixed position thereon by bolts 41, the undersides of the heads of which engage the flat end surfaces of the shaft 37.

Each of the differential pinions 36 has bearing portions 42 which extend beyond either of their faces and occupy the entire 95 space between the gear periphery and the web portions 33' thereof, with the toothed peripheries closer to the periphery of the bull gear 33 than to the hub thereof. A shaft 43 carries the bull gear 33, which is rotatably 100 mounted thereon.

Between the front frame plate 13 and the front end of the hub of the bull gear, a spur gear 44 having a forwardly extending hub portion 45, is rotatably mounted on the shaft 105 43, the forward end of the hub 45 bearing on the rear of the front frame plate 13, and the rear face of the gear 44 at the hub bearing on the forward end of the hub of the bull gear. The teeth of the spur gear 44 110 are meshed with both differential pinions 36. Secured fixedly to the hub portion 45 of the gear 44 and forwardly of this gear, is a smaller spur gear 46. Rotatably mounted on the shaft 43 between the rear plate 14 115 and hub 34 of the bull gear, is a spur gear 47, having a rearwardly extending hub portion 48, the rear end of which bears on the front face of the rear frame plate 14 while the front face of the gear 47, at the hub 120 bears on the rear end of the hub of the bull gear 33. The differential pinions 36 mesh with the gear 47. The rearwardly extending hub portion 48 of the gear 47 carries thereon and fixedly secured thereto, a larger 125 spur gear 49, having a series of rearwardly extending circumferentially spaced pins 51. The purpose of these pins will be hereinafter described.

Referring now to Figures 2 and 4, the gear 130

46 meshes with a gear 52 on an arbor 53, the gear 52 in turn meshing with a gear 54 on an arbor 55 which carries the main spring mechanism, generally indicated at 56. The arbor 55 extends into a main spring barrel 57 where it has connection with the inner end of the main spring at 58. The outer end of the main spring is suitably connected with the main spring barrel 57, the cover 59 of which extends radially beyond the edge thereof and is formed with circumferential gear teeth 61.

A collar 62 suitably splined or otherwise connected to, the arbor 55 in any suitable manner for rotary movement therewith and sliding movement therealong, has a threaded rear portion 63 which engages internal threads in a boss 64 extending forwardly from the cover 59. The collar 62 has at its forward end a radially extending flange 65, the rear face of which bears against a fork 66 of a brake supporting lever 67 pivoted to a supporting post 68 secured to the forward frame plate 13, at 69. The brake supporting lever 67 is normally spring projected forwardly by a flat spring 71 suitably secured thereto at 72 with its free end abutting the rear end of the post 68. A brake 73 is adjustably secured to the lever 67 at 74 and carries thereon a brake shoe 75 which is adapted to engage the forward face of the gear 23 as the main spring approaches its fully wound condition to brake the operation of the winding motor 16 and to stop the latter when the main spring is in fully wound condition.

A pinion 76 on a cannon pinion arbor 77 meshes with the gear on the main spring cover plate 59 and transmits motion to the arbor 77 to which, near the forward end thereof and behind the front frame plate 13, a gear 78 is secured. The latter gear meshes with a pinion 79 on an arbor 81 to which a gear 82 is also secured and which transmits rotary movement to a pinion (not shown) on an arbor 83. The latter arbor has secured thereon a gear 84 which meshes with a pinion 85 of an escapement mechanism 86. The mechanism thus far described completes the train of gearing leading from the winding motor to the main spring and to the escapement mechanism.

Referring now particularly to Figures 3 and 5, the gearing arrangement for the striking mechanism comprises a pinion 91 on an arbor 92 which meshes with the gear 49 of the differential 34. A large gear 93 fixed to the arbor 92 meshes with a pinion 94 on an arbor 95 which carries a gear 96 meshing with a pinion 97 on an arbor 98. The latter arbor carries thereon a vane type, air beater governor 99. The arbor 95 carries thereon and secured thereto, a stop arm 101 adjacent the gear 96 and which is adapted to rotate in a plane between the gear 93 and the for-

ward edge of the governor 99, so that it is positioned proximately to the forward frame plate 13. The gear 93 is provided with a forwardly projecting pin 102 near its periphery and which projects into a circular groove 103 provided on the rear side of the front frame plate 13. The free end of pin 102 is spaced from the side and bottom walls of the groove 103 and its path is circular about the arbor 92. The latter arbor has secured thereto on its forward end, which projects through the front frame plate 13, a cylindrical head member 104 which carries a forwardly projecting pin 105 thereon, eccentrically mounted with respect to the arbor 92. The purposes of the pins 102 and 105 will be hereinafter explained.

An arbor 106 mounted adjacent the periphery of the frame plates 13 and 14, and bull gear 33, carries thereon a dog 107 having a shoulder 108, against which one end of the flat spring 109 bears with the other end seated in a recess (not shown) in the rear frame plate 14.

The projected end of the dog 107 engages the teeth of the bull gear 33 preventing its rotation in unwinding direction while permitting rotation thereof in winding direction.

The rear frame plate 14 has a radial outwardly extending integral projection 111 thereon, in proximity to the differential 34. A stop or dog member 112 is pivoted to the front face of the rear frame plate 14 at a point 113 spaced radially and inwardly of the projection 111. This stop member comprises a bell crank having an arm 114 which has a perpendicular forwardly extending projection 115, and a laterally extending arm 116 having a T-shaped head portion 117 which has rearwardly bent arms 118 and laterally extending projections 119. The forwardly extending portion 115 is of sufficient length to act as a stop or abutment member for the pins 51 when it is swung into the path thereof by rotation about the pivot 113. The arms 118 which project into the plane of the rear frame plate 14, are adapted to abut the radial edges of the projection 111 to stop the stop member 112 in its operative and inoperative positions. The projections 119 extend beyond the outer edge of the projection 111 and can be easily gripped by the fingers of an operator to move the stop member 112 about its pivot 113 to operative or inoperative position. When swung to operative position, upon engagement of the stop portion 115 with any of the pins 51, the striking mechanism is made inoperative when so desired.

Referring now more particularly to Figures 2, 3 and 7, the audible signal producing means comprises a pair of bell striking hammer arms 121 and 122, the actuation of the two in unison constituting the hour strike and arm 122 being actuated alone to constitute the

half-hour strike. At their outer ends, arms 121 and 122 are provided with suitable hammers 125 and 126 respectively, which are adapted to be raised and dropped upon gongs 12 and 11 respectively. The intermediate portion of arm 122 is reversely bent to form a U-shaped portion 123 which is suitably seated within an arm 124 suitably secured to an arbor 127 journaled in the front and rear frame plates adjacent the differential 33 in proximity to the peripheries of the frame plates, arm 124 being disposed adjacent rear frame plate 14 and having a portion 128 adapted to be disposed normally in the path of movement of pins 51 or gear 49. The inner end of arm 122 is formed into an arcuate portion 129, the purpose of which will be hereinafter described. Arm 121 is likewise provided with a reversely bent U-shaped portion 131 (see Figure 2) the legs of which are embraced by two rolled ears 132 formed from laterally projecting lugs extending from one leg 133 of a U-shaped supporting member 134. This member 134 is mounted for pivotal movement about arbor 127 with leg 133 in abutment with the front face of arm 124, the other leg 135 being disposed in proximity to the rear face of the front frame plate 13. Leg 133 is also provided with a laterally extending lug 136 having a rearwardly bent end portion 137, one edge of which is adapted to normally abut the adjacent edge of arm 124. Leg 135 is provided with right-angularly extending arm 138 having a forwardly extending lug 139 at its free end. This lug 139 extends forwardly through an arcuate slot 188 in the front frame plate 13 and for a short distance beyond the front face of said frame plate (see Figure 1). The purpose of arm 138 and lug 139 will be hereinafter described. The inner end of arm 121 is also provided with an arcuate portion 141. Rolled ears 142 extending laterally from leg 135 are provided for alternate positioning of arm 121. The arcuate portions 129 and 141 are eccentrically disposed with respect to arbor 127 and in the inoperative positions of arms 121 and 122 are disposed in the same plane. It will be now apparent that since member 134 is freely rotatable on arbor 127 while arm 124 is secured to the arbor, and further since lug 137 has merely abutting engagement with arm 124, when arm 124 is cammed downwardly by pins 51, both arms 121 and 122 are elevated in unison. As each pin releases arm 124 in passing, both arms 121 and 122 are gravity actuated downwardly by the weight of hammers 125 and 126, striking bells 11 and 12 at the bottom of each stroke. The operation of gear 49 carrying pins 51 is so controlled as to stop the gear with one pin 51 in engagement with the upper edge of arm 124 and with both hammers 125 and 126 in raised position. The object of this arrangement will be hereinafter described in conjunction with the de-

tailed description of the operation of the clock and control mechanism. To prevent arms 121 and 122 from descending farther than is required to give an audible signal by striking the gongs 11 and 12, and to further limit the downward movement thereof in shipping of movements independently of the cases, a stop pin 143 is supported by and between frame plates 13 and 14 in parallel relation with arbor 127 and in the path of the arcuate portions 129 and 141 of arms 121 and 122.

I shall now describe the control mechanism for the striking mechanism, reference being had particularly to Figures 1 and 4.

It will be understood that the control mechanism is positioned on the front face of the frame plate 13 between this plate and the dial, with only those parts projecting through the front frame plate as will be so indicated. Pivoted on the outer face of the front frame plate 13 are three levers 151, 161 and 171 pivoted at 152, 162 and 172 respectively.

Lever 151 has a downwardly extending arm portion having an extension 153 which carries a pivoted spring projected arm 154. The extreme end of the lever 151 has a stop projection 159 against which a lug 155 of the arm 154 is adapted to abut in projected position. Intermediate the ends of lever 151, a perpendicular rearwardly extending stop lug 156 is provided. This lug extends through a slot 157 in the front frame plate 13 and is adapted to be moved into the path of a stop arm 101 against the pressure of a spring 181. The lug 156 is spaced from the arm 151 to form a recess seat 158 for a purpose to be hereinafter described.

Lever 161, pivoted at 162, extends downwardly and at its free end is provided with an arcuate toothed sector or rack 163, so that the lever is generally L-shaped. Intermediate the ends of lever 161, a finger 164 is pivoted at 165 and is normally spring projected through the action of a spring 167 against a stop lug 166 projecting forwardly from the lever 161, so that it can be temporarily moved downwardly out of the path of the high point of a cam 182 in each rotation of the latter. Adjacent the pivot 162, the lever 161 is provided with a rearwardly projecting lug 168. Spring 167 is coiled about the pivot 162 with one end thereof abutting the lower edge of the lug 168 and the other extending through a recess in a rearwardly projecting lug 169 on the finger 164. The teeth of the rack 163 project into the path of movement of the pin 105.

Spring 181 is coiled about the pivot 151 with one end abutting the upper edge of the lug 168 and the other passing through a recess in the lug 155, with the intermediate portion thereof passing under the lug 156 through the recess seat 157 and is offset

at this point to extend above the extension 153 of lever 151. The spring 181 is stouter than spring 167, thus acting to normally swing lever 161 toward the cam 182.

8 A third lever 171, pivoted at 172, is provided with a weight 173 at one end on one side of the pivot and at its other end, with three lugs 174, 175 and 176, the first and third of which project forwardly while the 10 second projects rearwardly through a recess 177 in frame plate 13 and is adapted to be moved into and out of the path of movement of pin 102. Lug 176 has a beveled edge 178 and is adapted to be moved into and out 15 of engagement with the teeth and the end of rack 163 of lever 161. Lug 174 projects into the path of movement of lever 151 and is adapted to be engaged by the lower edge thereof. Due to its weighted end, the lever 20 171 is normally gravity actuated so that there is always a tendency on the part of this lever to project its other end upwardly for engagement with the teeth of the rack 163 or the lever 151, when not positively actuated 25 in the opposite direction.

A fourth lever 183 pivoted at 184 on the frame plate 13 and spaced therefrom is of bell crank formation having its longer arm 185 extending downwardly and its shorter 30 arm 186 extending laterally adjacent and above the cannon pinion assembly, the latter arm being in constant engagement with an eccentric cam 187 on the cannon pinion assembly. (See Figure 4). Due to the positioning of this arm, it is constantly gravity actuated downwardly, so that the longer arm 185 may be moved into and out of a position overlying the slot 188 in the frame plate 13.

The cannon pinion assembly comprises a 40 minute hand shaft 191 projecting forwardly through the frame plate 13 and supporting a minute hand 192 at its outer end, any conventional hour hand gearing operatively connecting this minute hand shaft with the hour hand 193 (see Figure 4). As illustrative of this gearing, a pinion 194 on the minute hand shaft drives a gear 195 which, through pinion 196, drives a large gear 197 mounted on a sleeve 198. The stepped cam 182 is provided 50 on the cannon pinion assembly and rotates in the plane of the finger 164, thus being positioned forwardly of and rotating with the gear 197. A drop-off cam 199 is positioned adjacent and behind the cam 187. The cam 55 199 is provided with two cam shoulders and is of the type which operates its follower, in the instant case the finger 154, through two cycles of operation each revolution. Thus, the lever 151 may operate through two cycles 60 of operation for every revolution of the cam 199.

The operation of the winding and striking mechanism is as follows:

Assuming that the striking mechanism is 65 stationary after a striking period, the cam

follower or finger 154 having passed over one of the high points and dropped to a low point of the cam 199, and the brake 73 is slightly released, the motor 16 will wind the main spring through the train of gears 23, 26, 29 70 and 32, the last of these being in engagement with the bull gear 33 of the differential 34. At this time, the striking mechanism is held in inoperative condition by the engagement of lug 175 of the lever 171 with the pin 102, 75 thus retaining the gear 49 in stationary condition.

As the bull gear 33 is rotated, the pinions 36 carried thereby, impart rotary movement to the gear 44, employing the teeth of gear 47 as a track therefor. The gear 46 moving with gear 44, rotates the gear 52, which in turn rotates the main spring arbor 55 by co-action with the gear 54 fixed thereon. As the main spring is wound, the collar 62 threads 80 into the boss 64 carrying the fork 66 of the brake arm 67 rearwardly thus applying the brake 73 to the gear 23 and slowly retarding the winding. The deceleration of the motor 16 thus slowly approaches to a full stalling 85 condition as the collar 62 moves further into the boss 64 until a full stop is reached.

It will be apparent that the main spring will deliver energy to the escapement mechanism 86 continuously through the gear 95 trains 61, 76, 78, 82, 84 and pinion 85, all driven from the teeth 61 of the main spring cover plate 59.

Assuming now that the minute hand 192 has just passed the three-quarter hour mark and 100 is in the position shown in Figure 1, the cam follower or finger 154 is at this time resting on one of the high points of the cam 199, and in reaching this position has released lever 161 by the engagement of the lower edge of 105 lever 151 with the lug 174, thereby moving the upper end of lever 171 downwardly against the action of the weight 173, moving the lug 176 out of the path of movement 110 of the rack 163.

The lever 161 is thus spring projected to the left by the action of the upper free end of the spring 181 in abutment with the upper edge of the lug 168 so that the end of the finger or lever 164 abuts one of the steps of the cam 182, in the illustrated position, the eleven o'clock step. The rack is at this time advanced inwardly so that the proper number of teeth thereon are presented to the pin 105, the coaction of which will be presently 115 described. At this time the arm or lug 156 of lever 151 is in a position in the path of movement of the stop arm 101 (see Figure 3) thereby preventing the striking mechanism 120 from operating.

As the minute hand 192 reaches the hour mark, the cam follower 154 drops off the high point on the cam 199 and is projected upwardly by the spring 181, thus moving the lug 156 out of the path of movement of the 125

arm 101 and permitting the striking mechanism to operate.

With the arm 101 released, the gear train from the main spring arbor back to the differential is free to operate so that the gear 54 under the expansion influence of the main spring is rotated in a direction reversed from that in winding and transmits rotative energy to the gear 52 which in turn rotates gear 46 (see Figure 2).

The bull gear 33, which is prevented from reverse rotation by the dog 107, now remains stationary so that the differential pinion pivots remain stationary. With the pinions 36 thus permitted to rotate about stationary pivots, the gear 44 moves in a clockwise direction as seen in Figure 2 with its companion gear 46 and through the differential pinions, rotates the companion gears 47 and 49 in a counter-clockwise direction as viewed in Figure 3. The pins 51 each in turn engage the upper edge of the arm 124 causing both hammers of the striking means to be raised as each pin reaches its lowest position, the hammers 125 and 126 being permitted to fall suddenly by the disengagement or release of the arm 124 from the pin.

During the striking operation, the gear 49 through pinion 91 rotates arbor 92 in a clockwise direction, thus rotating the pin 105 on the head portion 104, which at the top of its path of movement engages the teeth of the rack 163. As the rack 163 is moved to the right, the beveled edge 178 of the lug 176 is engaged by each successive tooth of the rack, and end of lever 171 being cammed downwardly in passing, and dogging the rack against return movement after each tooth passes by the lug 176. The relationship between each striking impulse transmitted to the hammers by each pin 51 is such as to account for one complete revolution of the arbor 92, and consequently pin 105, which in turn upon each revolution moves the rack 163 one tooth to the right, each tooth accounting for one strike and thus controlling the number of strikes to be made by both hammers in unison.

When the lug 176 has passed the end tooth 179 of the rack, the weight 173 acts to raise the right hand end of the lever 171 until the lug 174 thereon abuts the lower edge of the lever 151. At this time the lug 175 is elevated by the movement of lever 171 into the path of movement of the pin 102 and stops the striking mechanism when the pin 102 abuts the lug. During the striking operation the gear 96 on arbor 95, which is actuated by its pinion 94 coacting with gear 93, transmits rotary movement to the vane type air beater governor 99 by its engagement with pinion 97 on its arbor 98, so that the governor controls the speed and smoothness of operation of the striking mechanism.

The control parts are now in a position preventing the operation of the striking mechanism until the next striking interval is reached.

As the minute hand approaches the quarter-hour point, cam follower or finger 154 is again depressed against the pressure of spring 181, but the high point or cam 199 effective at this time is not quite as high as the one effective prior to the hour interval, so that lever 151 is not moved outwardly as far as prior to the hour interval. Hence lever 171 is not cammed downwardly by the engagement of the lower edge of lever 151 with lug 174, whereby lever 161 is not released for swinging movement to the left (see Figure 1). Lever 151 is, however, moved sufficiently to the right to cause the lug 175 to move out of the path of movement of pin 102 and to place the lug 156 in the path of movement of arm 101, (see Figure 3). Thus gear 93 will rotate slightly until arm 101 engages lug 156. At this time, cam 187 on the cannon pinion assembly will have permitted arm 185 to gradually drop to a position overlying slot 188 whereby the end of arm 185 assumes a position in the path of movement of lug 139 of the striker arm 121 mounting member 134.

When the minute hand passes the half-hour point, finger 154 suddenly drops off the respective high point of cam 199, thereby releasing arm 101 and permitting operation of the striking mechanism. This operation is, however, limited to one revolution of gear 93, due to the prompt raising of lug 178 by the action of weight 173 of lever 171 into the path of the end 179 of the rack 163 of lever 161, thereby permitting lug 175 to promptly assume its position in the path of movement of pin 102. This rotational movement of gear 93 is only sufficient to permit one pin 51 to ride over the edge of arm 124. Since arm 121 is at this time in elevated position, and arm 185 will permit but a slight movement of lug 139 in the arcuate slot 188, only arm 122 and its hammer 126 will drop, resulting in a sounding of only gong 11. The succeeding pin 51 of gear 49 will only engage arm 124 sufficiently as the striking mechanism is brought to rest to slightly raise both arms 121 and 122.

It will thus be apparent that two gongs giving a distinct harmonizing audible signal are struck on the hour, while only one gong is struck on the half-hour.

As the minute hand proceeds in its movement around to the three-quarter hour point, the control parts remain in the same position as they assume following an hour striking period hereinbefore described.

When the minute hand again reaches the three-quarter hour point, the cam follower or finger 154 is again depressed against the pressure of spring 181 moving the lug 175

out of the path of stop pin 102, lug 156 into the path of stop arm 101, and the lug 176 out of the path of the rack 163, whereby all striking control parts are restored approximately to the positions which they occupied previous to the prior hour striking operation. The rack, however, moves inwardly further than it did before owing to the fact that the finger 154 now strikes the next lower step of the stepped cam 182, the latter having revolved one-twelfth of a revolution with the rotation of the hour hand.

Hence in the next operation of the striking mechanism at the end of the hour period, the rack member 163 will have to be moved outwardly through the space of one more tooth before the lug 176 can swing upwardly in advance of the tooth 179, resulting in one more striking impulse being given the hammer 126, at the next striking operation. This extra impulse will be added to each successive hour striking operation from one o'clock to twelve o'clock, owing to the finger 164 moving inwardly to a greater degree in contacting with the successively lower step of the cam 182 at successive striking intervals.

It will be evident from the foregoing that the clock mechanism and striking mechanism both derive their operating energies from a single constantly energized electric motor so that the operation of the clock continues indefinitely without manual winding of any spring. The continuously acting torque of the motor effective on the main spring of the clock movement at all times excepting during a striking period, results in the tension of this clock spring being maintained between very close limits, approximating a uniform tension on the spring at all times. It will be apparent that this augments the time keeping accuracy of the clock. When the main spring tension is such that the spring is in fully wound condition, the forked end 66 of the brake lever 67 will have been moved rearwardly by the rearward movement of the collar 62 and its flange 65 impinging upon the fork 66 as the collar threads into its threaded boss, thus applying the brake 73 by the transmission of rearward pressure to the brake shoe 75 which will in turn frictionally impinge upon the gear 23, thereby stalling the motor.

The motor will remain in stalled condition until the brake 73 will have been moved forwardly slightly by the unwinding of the main spring, thus relieving the pressure on the gear 23, when the constantly energized motor will again energize the gear train to the differential.

Since the tension of the main spring is maintained between very close limits, it will be evident that the motor will energize the gear train to the differential at very short intervals. In view of this condition, it will be

further apparent that the motor will be active during practically every striking period.

While I have hereinbefore described the operation of each gear train, namely (1) from the motor to the main spring through the differential and (2) from the main spring to the striking mechanism, it will be understood, that while a condition may arise when each train may operate independently of the other, due for example to a failure of the current in the line an instant or so prior to the striking period and a resumption of the line current shortly after the expiration of a striking period, that generally in the normal operation of the device, owing to the frequency of the intermittent brake release, and the consequent energization of the gear train from the motor to the differential as hereinbefore explained, the striking operation will occur concurrently with the energization of the gear train from the motor to the differential.

During this concurrent operation, all the energy transmitted from the motor to the differential is taken up by the striking mechanisms due to the fact that the relative arrangement of the gear trains from the main spring to the differential and from the motor to the differential is such that even though the motor is operating, the main spring will still unwind slightly during a striking period. As viewed in Figures 2 and 3, during this operation, the bull gear 33 is rotated in a counter-clockwise direction. The relative movements of the various parts of the differential are such that with the bull gear turning in a counter-clockwise direction, the slight movement of the gear 44 in a clockwise direction due to the slight unwinding of the main spring permits the teeth of the gear 44 to act as a track for the pinions 36 so that the gear 49 rotates in a counter-clockwise direction. Upon such rotation of the gear 49, the pins carried thereby will operate the hour striking hammer through the coaction therewith of the arm 127.

It is to be noted, that since the energy transmitted by the motor during a striking period is entirely exhausted by the striking mechanism and that since the main spring is unwinding during the striking period, as soon as the striking mechanism ceases to operate by virtue of the stopping thereof by the automatic operation of the control means, the energy transmitted subsequently to the differential will be then directed through the main spring gear train from the differential to the main spring as hereinbefore described. When the main spring has been fully wound the motor will be installed by the application of the brake 73 upon the gear 23.

If it is desired to render the striking mechanism inoperative, the stop arm 114 may be rotated to the position indicated in dotted lines in Figure 3, when the lug 115 will lie

in the path of movement of the pins 51 and upon engagement thereof, the gear 49 will be prevented from rotation.

It will be evident from the foregoing that should the line current fail during a striking period thereby deenergizing the motor, the main spring will nevertheless carry over the operation of the striking mechanism, thus insuring a completion of the striking period regardless of the failure of the line current.

It is to be understood that the term "striking mechanism" is not limited to devices striking a gong, or to that part of the mechanism which operates upon an instrumentality acting as the source of an audible signal, for example such as the hammer, but is intended to embrace all forms of apparatus designed to audibly or otherwise indicate predetermined time periods in the operation of a clock.

So far as I am aware, I am the first in the art to provide a striking clock wherein the striking mechanism and clockworks are both actuated by the main spring and wherein a single constantly energized motor operates the striking mechanism during a striking period and is adapted to wind the main spring between striking periods.

The novel arrangement of gears and the interposition of the differential and the co-action therewith of the main spring of the clock by the slight unwinding of the latter during a striking period, renders the single motor sufficient for purposes of operating both the clock mechanism and the striking mechanism.

While I have shown what I regard as a preferred embodiment of my invention, it will be understood that modifications and rearrangements may be made therein by those skilled in the art without departing from the spirit and scope of the appended claims or the essence of the invention.

What I claim as my invention and desire to secure by Letters Patent is:

1. In combination, a clock movement, a main spring, connections between the two for operating the former by the latter, a striking mechanism, means for controlling the striking mechanism, a constantly energized electric motor, a gear train connecting the motor with the main spring for effecting winding of the spring by the motor, a differential in said train, and means on said differential for operating said striking mechanism, the differential transmitting all of the energy of the motor and a portion of the energy of the main spring to the striking mechanism during a striking period for operating said mechanism, should the motor fail, the differential transmitting energy from the main spring to the striking mechanism for operation thereof during a striking period, and should the main spring be unwound the differential transmitting en-

ergy from the motor to the striking mechanism for operating same during a striking period.

2. In combination, a clock movement, a main spring, connections between said movement and main spring for actuating the former by the latter, a striking mechanism, a governor, a constantly energized electric motor, a gear train between the motor and said main spring for effecting winding of the spring by the motor, a differential in said train, and a second gear train connecting said differential with said governor means on the differential for effecting operation of said striking mechanism during a striking period by the motor and the main spring under the control of said governor, the main spring being wound by the motor through the differential between striking periods, said gear trains and differential permitting the main spring to operate the striking mechanism during a striking period should the motor fail, and control means for the motor controlled by the main spring to stop said motor when the main spring is fully wound.

3. In combination, a clock mechanism having a main spring, a striking mechanism, means for controlling the striking mechanism, a constantly energized electric motor, a differential having a bull gear, and a spur gear on each side of the bull gear, a gear train connecting said motor with said bull gear, a gear train connecting said main spring with one of the spur gears, and a gear train connecting said striking mechanism control means with the other of said spur gears, to enable the motor and the main spring conjointly to operate the striking mechanism during a striking period through said differential and either the motor or the main spring, upon failure of the other, to operate said striking mechanism, said main spring unwinding during a striking period, the motor winding the main spring through the differential between striking periods, and means controlled by the main spring for stopping the motor when said spring reaches its fully wound condition.

In witness whereof, I hereunto subscribe my name this 10th day of April, 1930.

ROSCOE H. WILMETH.
